RAIN WATER CONDUCTOR OFFSET

Filed Sept. 22, 1930

INVENTOR.
EDWARD W. N. BOOSEY

BY

Edward E. Moore

ATTORNEY.

UNITED STATES PATENT OFFICE

EDWARD W. N. BOOSEY, OF DETROIT, MICHIGAN

RAIN WATER CONDUCTOR OFFSET

Application filed September 22, 1930. Serial No. 483,464.

This invention relates to rain water conductor offsets for buildings, and the object of the invention is to provide a rain water conductor offset adapted to extend through the wall of the building above the ground line to the interior thereof and so constructed and arranged to support the weight of the upper portion of the conductor.

Heretofore, rain water conductors, or "down spouts" as they are often called, extend from the eave trough to a crock at the bottom exteriorly of the building which discharges to a drain line usually above the floor of the basement.

15 In previous construction, such down spouts, especially when on the side of a building having a driveway, has the disadvantage of being subject to breakage or displacement by vehicles and has the further disadvantage 20 that, in the case of stoppage in the drain line, water may back up to a height above the basement floor causing damage. This invention seeks to obviate these difficulties by providing a fitting adapted to be placed in the 25 wall of a building and so constructed as to take both the side and down pressure resulting from the weight of the down spout above the fitting, and further to provide a construction wherein the rain water is discharged 30 through the usual drain lines in the basement which are protected from back pressure in the sewer by the usual back water check valve between the drain lines and sewer.

35 These and other objects and novel features of the invention are hereinafter more fully described and claimed, and the preferred form of construction of a rain water conductor or offset is shown in the accompanying 40 drawings in which—

Fig. 1 is a diagram showing the arrangement of the down spout from the side of the building including my improved fitting or offset and its connection with the drain lines 45 of basement.

Fig. 2 is an enlarged section taken on line 2—2 of Fig. 3.

Fig. 3 is an elevation of the external wall surface of a building and fitting supported 50 therein.

In Fig. 1, the wall of a building is indicated at 1 and the portion of the down spout is shown at 1a supported at the bottom in my improved fitting or offset 2, the body of which extends at an angle to the vertical 55 through the wall of the building. This fitting is preferably of iron and is formed with a step or base 3 intermediate its length having an integral face plate 4 connected with the base 3 and adapted to be positioned practically flush with the outer surface of the building as indicated in Figs. 2 and 3. This fitting, due to the body thereof lying at an angle and due to the pressure of the down spout which is inserted in the hub end 5 of 60 the fitting, has a tendency to slip in the wall and by the arrangement of the plate 4 and base 3 this pressure is transmitted to the wall which prevents longitudinal movement of the fitting through its aperture in the wall. 65

The fitting may be formed of two parts 2 and 2a connected either by means of the well known spigot joint or in the threaded relation shown in Fig. 2, the parts 2a having the vertical end portion 6 on the interior of the 70 building for connection with a conduit 7 which in turn is connected with a fitting 8 leading to the drain lines of the basement. The fitting 8 may be provided with a base 9 to take the weight of that portion of the conductor within the building and may also have an ordinary cleanout plug 11 above the floor line 10. It is not essential, however, that the fitting be formed of two parts 2 and 2a as said parts obviously may be made integral if so 75 desired.

It will be observed that, by the use of a fitting, particularly shown in Figs. 2 and 3, the down spout terminates at a point sufficiently above the ground level, as indicated at 10 in 80 Fig. 1, as to avoid its being damaged or displaced by vehicles along a driveway, and further that the rain water instead of being discharged into a drain line around the building usually above the floor line of the basement, 85 as has been the general practice, is by my improved offset carried to the interior of the building to position to be connected with the drain lines of the basement.

It has been usual heretofore in placing the 100

rain water drain line around the outside of the building foundation to excavate trenches at various points under the foundation which weakens the same. By my improved fitting 5 or offset I avoid the necessity for forming trenches under the wall and further provide a construction in which the weight of a down spout on the exterior of the building is taken by the building wall and it is further believed 10 evident from the foregoing description that other various features of the invention are likewise attained by the construction described.

Having thus briefly described my invention, 15 what I claim and desire to secure by Letters Patent of the United States is—

1. An offset for rain water conductors consisting of a tubular fitting, the opposite open ends of which face in the opposite direction 20 in the same plane, the body of the fitting extending therebetween on an angle to the axis of the said ends, one end thereof being formed to receive an end of a rain water down spout, the angular portion of the fitting having 25 a step or base for supporting the same in a wall and further having a plate adjacent the said end for engaging the face of a wall whereby the fitting is adapted to withstand pressures both vertically and horizontally.

2. An offset for rain water conductors consisting of a tubular fitting adapted to be inserted in the wall of a building above the ground line and to extend into the basement of a building, which consists of a tubular 35 member having its opposite open ends facing in opposite directions in a vertical plane, the outer end having a hub for receiving a down spout and the inner end being adapted for connection with a conduit leading to the drain 40 lines of the basement, the body of the fitting between the said ends extending at an angle to the vertical, and an integral plate adjacent the outer end of the fitting for engaging the face of a wall, and a step portion for supporting the fitting in the wall whereby the fitting is adapted to withstand pressure both vertically and horizontally.

3. An offset for rain water conductors consisting of a tubular fitting adapted to be inserted in the wall of a building above the ground line and to extend into the basement of a building, the body of the fitting extending through the wall at an angle to the vertical, the said fitting being formed of two parts 50 adapted to be connected together in watertight relation, a supporting element consisting of a foot or base positioned in the wall, and an integral vertical plate adapted to engage the face of the wall, the foot and plate 55 preventing slippage of the fitting in the wall.

In testimony whereof I sign this specification.

EDWARD W. N. BOOSEY.
